(57) **CLAIM**

The ornamental design for a cable tester as shown and described.

DESCRIPTION

1. Cable tester
- 1.1 : Perspective
- 1.2 : Perspective
- 1.3 : Front
- 1.4 : Back
- 1.5 : Left, showing the two components of the cable tester in a stacked configuration
- 1.6 : Right, showing the two components of the cable tester in a stacked configuration
- 1.7 : Top
- 1.8 : Bottom
- 1.9 : Perspective view shown in an assembled state
The broken lines in the reproductions depict portions of the cable tester that form no part of the claimed design; the explanatory curved bracket in the reproductions shows the association of elements and forms no part of the claimed design.

1 Claim, 9 Drawing Sheets
